UNITED STATES PATENT OFFICE.

ARTHUR E. MILLER, OF SACRAMENTO, CALIFORNIA.

COMBINATION-LOCK.

1,370,830.

Specification of Letters Patent.

Patented Mar. 8, 1921.

Application filed May 3, 1920. Serial No. 378,503.

To all whom it may concern:

Be it known that I, ARTHUR E. MILLER, a citizen of the United States, residing at Sacramento, in the county of Sacramento and State of California, have invented certain new and useful Improvements in Combination-Locks, of which the following is a specification.

This invention relates to certain new and useful improvements in permutation locks of substantially the type shown, for instance, in the former Patent No. 1,312,938, dated August 12, 1919; although the several improvements which I will hereinafter describe are applicable to other forms of so-called combination locks and hence may be applied thereto without departure from the salient features of the present invention.

An essential object of the invention I am about to describe is to simplify and render more effective for the intended purposes, a lock of the character before referred to, and to provide increased security to the lock and to make it more certain of operation and more difficult for the lock to be opened by an unauthorized person.

With the above and other objects in view, my invention consists of the parts and the constructions, arrangements and combinations of parts which I will hereinafter describe and claim. In the accompanying drawings forming part of this specification and in which similar reference characters indicate like parts in the several views;

Figure 1 is a longitudinal sectional view of a lock embodying my invention and associated with parts of the steering elements of an automobile.

Fig. 2 is a plan view and edge view partially in section of the outer tumbler of my lock.

Fig. 3 is a plan view and edge view partially broken away of the inner tumbler.

Fig. 4 is a perspective view of the protector ring.

Fig. 5 is a plan view of a stationary tumbler of modified form.

Fig. 6 is a sectional view of the same.

Fig. 7 is a sectional view of a further modified stationary tumbler.

Fig. 8 illustrates a modified construction of the head of the main operating bolt.

Fig. 9 is an enlarged detail to be herein-after referred to.

Fig. 10 illustrates a fragment of the lock-

ing bolt in association with safety locking sleeves on the steering post.

For present purposes, I have shown my improved lock in association with features which constitute a safety locking mechanism for the steering post or element of an automobile or like vehicle, but to this particular use the invention is not to be considered as restricted, since the improvements I will hereinafter refer to relate to the lock itself rather than to the features which connect the same to the steering post or element.

In carrying out my invention, I provide the lock with a casing of suitable size and design. A casing substantially of the type shown in the prior patent mentioned, I have illustrated herein as it will answer my present purposes. This casing, 2, is made with a rigid base portion, 3, which forms a member of a clamp, and is shown hollowed out so that it may fit the rounded surface of the usual housing, 4, which covers the steering post, 5. The other member of the body of the lock is in the form of a strap or clamp, 6, which fits the opposite side of the housing, the strap and the base of the lock case being rigidly secured together by suitable screws, 7.

The lock case has an internal bore sufficient to operatively contain the tumblers and other active parts of the lock, the outer end of the case being recessed at 8, while at the bottom of this recess there is an inwardly projecting flange, 9, forming a stationary tumbler, having an opening, 10. Within the lock case is a bolt, 11, adapted for both axial and longitudinal movement, said bolt carrying an enlarged head, 12, at its outer end adapted to the recess, 8, and designed to be supported, at times, on the flange, 9, or stationary tumbler, said bolt having a transversely extending pin, 13, adapted by the rotation of the bolt to be brought into register with the opening, 10, in the flange, 9, to thereby permit the bolt to be moved longitudinally and its pin, 13, to pass through said opening and when the bolt is partially rotated, to be seated on the outer surface of the flange thereby holding the bolt in a retracted open position.

Within the lock casing and, preferably, just under the flange, 9, is a bushing or protector ring, 14, which is tightly fitted in place and has its inner circumference pro-

vided with an annular series of parallel radially disposed grooves, 15, adapted to be engaged by a loose ball, 16, carried at the outer end of a tube, 17, fixed to the bolt and 5 extending radially therefrom, said tube containing a spring, 17', which forms a yielding seat for the ball and insures said ball being maintained in contact with the grooved, inner surface of the bushing, so that during 10 the rotation of the bolt, 11, in working the combination, the ball will be caused to ride over the grooves in the bushing and by the clicking sound thus produced and the vibration conducted through the bolt to the operating milled head thereof and the operator's fingers will aid the operator in working 15 the combination even in the absence of light sufficient to enable the combination to be read from the usual indicia on the head 20 of the bolt and on the casing surrounding said head, as will be readily understood by those skilled in the art. A portion of the inner surface of the ring, 14, is left smooth at 18, say by eliminating two or more of the 25 grooves. This is to enable me, in practice, to use numbers 1 to 20, instead of any zeros in the indicia on the outer face of the lock casing and to have the number "20" indicating this portion, 18. In operation, the 30 passage of the ball over the grooves is indicated by touch and sound as each groove is passed and this assists the operator in working the combination.

On the bolt, 11, just below the protector 35 ring or bushing, 14, is a loose washer, 16^a, and below this are the tumblers, which constitute a prominent feature of my present invention. These tumblers, 18, 19, are concentrically arranged, as in the prior patent 40 mentioned, and their detailed construction is shown in Figs. 2 and 3. The tumblers are stepped or flanged so that one fits smoothly within the other and when assembled their top and bottom faces are substantially flush. 45 The inner tumbler, 18, has an opening, 20, through its outer side and the outer tumbler, 19, has a like opening, 21, through its inner side, which openings are designed to be brought into register to enable the main bolt 50 to be moved in the direction of its length.

The inner tumbler, 18, is also provided with an annular series of holes, 22, adapted for the reception of a pin or pins, 23, in changing the combination which controls 55 the lock. The series of holes, 22, are formed in an annular shoulder or stepped portion, 24, formed by reducing the diameter of the tumbler at this point and the pin or pins, 23, accordingly extend parallel with the main bolt and project a desired distance 60 beyond the face of the tumbler to enable it to be engaged by a pin, 25, on the companion outer tumbler, said pin, 25, in the present instance, however, projecting radially of the 65 axis of this tumbler and substantially at

right-angles to the pin 23, of the inner tumbler, and being parallel with and operating over or close to the annular shoulder, 24, and in the path of movement of the pin, 23, of the rotatable inner tumbler, said latter 70 pin, 23, being engaged by a radial pin, 26, on the main operating bolt. In operation, the rotary bolt is turned, say to the right, until the usual pointer, 12', on the head, 12, registers with the proper character or unit, 75 2', of the combination, on the lock casing; during this movement the radial pin, 26, has engaged the pin, 23, of the inner tumbler and rotated said tumbler to first bring its pin into engagement with the pin 25, of the outer tumbler and then to give motion to both tumblers, the motion being continued until the second character of the combination is reached, which positions the opening, 21, in said outer tumbler. Then the bolt is 80 turned to the right until its radial pin, 26, engages the pin, 23, of the inner tumbler from the opposite side, thus giving motion to this tumbler and bringing its opening, 20, into register with the like opening, 21, in the outer tumbler. When this described position of the openings, 20, 21, has been secured, 85 and the radial pin, 26, registers therewith, the bolt, 11, is in position to be withdrawn from its locking engagement with the locking recess in the steering post, as will be readily understood; during this actuation of the tumblers, the radial pin, 13, has also been brought into register with the opening, 10, in the stationary tumbler or flange, 9, so 90 that it may also pass therethrough and be seated on the outer surface thereof to support the bolt in its withdrawn position. To reset the lock, the bolt is rotated until its pin, 13, registers with the opening, 10, when the bolt may be pushed in until its end enters the locking recess in the part to be secured and the tumblers "scattered" by the rotation 95 of said bolt.

The outer tumbler also has an annular 100 flange, 19', forming a seat for one end of a spiral spring, 28, which supports the tumblers, said spring having its opposite end seating against a loose disk, 29, which in turn is adapted to an annular seat, 30, on the 105 inner end of the lock casing, said disk, 29, having a central opening for the passage of the inner end of the locking bolt, 11, and having a flange or collar, 31, surrounding 110 said opening and adapted to enter the hole 115 in the steering post housing, 4.

The purpose of the collar, 31, of my improvement will be understood from the following: If force is applied to a lock with a view of turning its casing on the steering 120 post housing when the latter is locked, the housing might be bent slightly and if so the easy operation of the bolt might be affected by the tendency of the bolt to bend, but the 125 collar bears against the wall of the recess 130

for the bolt and takes the strain arising from any forcible attempt to turn the lock on the housing, and thus relieves the bolt from lateral strain and insures its easy and 5 true operation at all times.

In Fig. 5 I show a modification of the stationary tumbler shown in Fig. 1. In this modified construction the tumbler, 32, has formed in its underside a number of depressions, 31^a, one of these depressions being cut entirely through the tumbler to form the opening, 33', for the passage of the radial pin, 13, on the head of the bolt, and which pin operates just beneath the 10 tumbler. Sometimes a lock is opened by pulling up strongly on the head of the bolt and working the bolt around to the right and left back and forth, when the openings, 20, 21, in the tumblers are sometimes brought into alinement and the bolt 15 permitted to be withdrawn. By making the stationary tumbler with its depressions, 33, when the bolt is rotated, the radial pin, 13, thereof will enter one of the notches or 20 depressions in the stationary tumbler and it is then impossible to turn the head of the bolt until the bolt is forced into its proper place when no amount of turning will affect the 25 relation of the two movable tumblers. The opening, 33', in the stationary tumbler is for the passage of the radial pin, 13, in the same manner as described for the like opening of the tumbler or flange, 9, of Fig. 1. The depressions may be in one or both sides of the 30 stationary tumbler, a tumbler having its top surface also provided with depressions, 34, being shown at 35, in Fig. 7. An object of these depressions is, accordingly, to prevent 35 accidental locking of the bolt when unlocked, as will be readily understood by those skilled in the art.

Instead of making the stationary tumbler in the form of a flange that is integral with the lock casing, I have shown in Figs. 5, 6 40 and 7, said tumbler as being in the form of a separate washer which is forced into the casing and fits snugly up against the aforesaid flange so that if the head of the bolt is pulled upwardly when the combination is 45 being worked, the radial pin, 13, will enter one of the notches in the washer and prevent further movement of the locking pin, unless that notch is the one which is in register with the opening, 10, in the flange for 50 the passage of the radial pin. When made as a separate washer or disk, as last described, the notched tumbler will be held in place by the bushing or indicator ring, 14, as shown, this ring being forced into the 55 barrel of the lock just below the washer.

In some instances I may wish to change the location of the indicator ring and the spring-pressed ball which clicks past the grooves in this ring, and hence in Fig. 8, I 60 show the indicator ring, 36, or bushing as

surrounding the head of the lock-bolt, and in the head of this bolt is a bore, 37, which contains the spring for pressing the ball, 38, into contact with the grooved surface of said ring. In said Fig. 8, I also show the 70 head of the locking bolt as being made of separable parts, the outer part being in the form of a cap, 39. In this instance, the main part of the head carries a pin, 39^a, which may serve as the means for turning the 75 head, even after the cap is removed. That this phase of the invention may be better understood, I will say that if great force is exerted by means of a wrench or otherwise upon the head of the locking bolt, there is 80 a possibility of the radial pins or some of the parts of the bolt being broken or bent so as to prevent the successful manipulation of the lock in the usual manner, but with a cap made and applied to the head of the 85 bolt, as indicated, when force is exerted upwardly on the cap, instead of this resulting in the breaking of one or more of the pins of the bolt or the lock mechanism, the cap would be separated from the head proper of 90 the bolt, but leaving the pin, 39^a, exposed so that it could be grasped by the fingers for rotating the bolt the head of which might be flush with or slightly below the outer end of the barrel of the lock casing, where it 95 could not be readily grasped by the fingers for turning purposes. When using the cap shown in Fig. 8, its under surface will rest on top of the indicator ring or bushing, 36, an arrangement which will permit the lock 100 to be shortened to some extent and may cheapen the cost of construction, both of material and labor.

In Fig. 10, I show in connection with the steering post and its housing the segmental 105 safety sleeves, 40, 41, of my former application, Serial Number 371,695, filed April 6, 1920, and with which construction I may use the present lock improvements, if desired.

Having thus described my invention what 110 I claim as new and desire to secure by Letters Patent is:—

1. In a lock, the combination with a casing and an operating bolt therein capable of rotary and longitudinal movement, and 115 provided with a radial pin, of a pair of co-acting tumblers arranged concentric with the bolt and with each other, said tumblers having pins one arranged crosswise of the other and actuated thereby and said tumblers 120 having registering openings in their inner faces for the reception of the radial pin of said bolt.

2. In a lock, the combination with a casing and an operating bolt therein capable of 125 rotary and longitudinal movement, said casing having a recessed head portion and a stationary tumbler arranged thereunder and provided with a radial opening, said bolt having a radial pin adapted to register with 130

- said opening, of a pair of coacting movable tumblers arranged concentric with the bolt and with each other, said movable tumblers having pins one arranged crosswise of the other and actuated thereby, said tumblers having openings in their under faces opening through the periphery thereof, and a second radial pin on the bolt adapted to enter said opening when in register therewith.
- 10 3. In a lock, the combination with a casing and a bolt therein capable of combined rotary and longitudinal movement, said bolt having a radially-extending pin, of a pair of coacting movable tumblers one mounted concentrically within the other, one of said movable tumblers having an annular shoulder provided with a series of holes and a pin adapted to said holes, and the other movable tumbler having a pin projecting from its inner circumference at right angles to and across the path of movement of the pin of the companion tumbler, said bolt having a radially projecting pin adapted to engage the pin of the first-mentioned tumbler.
- 15 4. In a lock, the combination with a casing and an operating bolt therein adapted for rotary and longitudinal movement, said bolt having a radially projecting pin, of inner and outer tumblers, one supported concentrically on the other, said inner tumbler having an exterior annular shoulder provided with a series of holes, and a pin adapted to said holes and extending parallel with the axis of the tumbler, and said outer tumbler having a pin projecting radially from its inner circumference across said shoulder and into the range of action of the first-named tumbler pin, each of said tumblers having an opening adapted to be brought 20 into register for the reception of the radial pin of said operating bolt.
- 25 5. In a lock, the combination with a casing, an operating bolt therein capable of rotary and longitudinal movement, and complementary tumbler mechanism in said casing, of an indicator means in the head of the lock casing and comprising a ring fixed in the casing and having a grooved inner circumference, and a radially-actuated spring-supported sphere carried by the bolt adapted to operate crosswise over the grooves of said ring, said ring having, also, a minor portion of its surface plain and ungrooved and over which the sphere also operates.
- 30 6. In a lock, the combination with a casing, an operating bolt capable of rotary and longitudinal movement and complementary tumbler mechanism in said casing, of a part to be locked, said part having an opening to receive the end of said bolt, and a loose disk having an open center in which the bolt 35 freely rotates, said loose disk having a collar surrounding its central opening and adapted to enter the opening in the part to be locked.
- 35 7. In a lock, the combination with a casing, an operating bolt therein having an enlarged head on the outer end, a cap member on the head of the bolt, complementary tumbler mechanism in the casing, a radial pin on the bolt for actuating the tumbler mechanism, a stationary tumbler in the head end 40 of the casing, and provided with an opening, said bolt having a radial pin adapted to said opening, an indicator ring concentric with the axis of the bolt and having an annular series of parallel grooves in its inner circumference, and a radially operating yieldingly supported sphere carried by the bolt and adapted to sweep transversely over said surface of the indicator ring.
- 45 8. In a lock, the combination with a casing, an operating bolt capable of rotary and longitudinal movement and complementary tumbler mechanism in said casing, of a part to be locked, said part having an opening to receive the end of said bolt, and a loose disk having an open center in which the bolt 50 freely rotates, said loose disk having a collar surrounding its central opening and adapted to enter the opening in the part to be locked.
- 55 9. In a lock, the combination with a casing, an operating bolt therein having an enlarged head on the outer end, a cap member on the head of the bolt, complementary tumbler mechanism in the casing, a radial pin on the bolt for actuating the tumbler mechanism, a stationary tumbler in the head end 60 of the casing, and provided with an opening, said bolt having a radial pin adapted to said opening, an indicator ring concentric with the axis of the bolt and having an annular series of parallel grooves in its inner circumference, and a radially operating yieldingly supported sphere carried by the bolt and adapted to sweep transversely over said surface of the indicator ring.
- 65 10. In testimony whereof I affix my signature.
- ARTHUR E. MILLER.
